UNITED STATES PATENT OFFICE.

SAMUEL I. BAER, OF YOUNGSTOWN, OHIO.

COMBINATION ARMOR AND INNER LINER.

1,372,858.

Specification of Letters Patent. Patented Mar. 29, 1921.

Application filed January 17, 1921. Serial No. 437,767.

To all whom it may concern:

Be it known that I, SAMUEL I. BAER, a citizen of the United States of America, residing at Youngstown, in the county of Mahoning 5 and State of Ohio, have invented certain new and useful Improvements in Combination Armor and Inner Liners, of which the following is a specification.

My invention relates to improvements in 10 inflatable tires of that class wherein an inner tube is designed to be inflated by pumping air into the same; and the object that I have in view is to provide an improved means for preventing the inner air-tube 15 from being penetrated or punctured by tacks, nails, or other sharp objects, but without appreciably detracting from the resiliency or elasticity of the tire.

In my invention I provide an armor as a 20 protection for the inner tube and at the same time an inner liner reinforcing the casing, ordinarily incasing the inner tube. In order to do this I have provided an armored inner liner comprising a series of 25 three differently formed overlapping plates arranged and combined in a novel manner to afford protection to the inner air chamber or space of the tire and allow the tire to have the expansion and freedom of movement necessary in tires for vehicles.

To enable others to understand my invention, I have illustrated the preferred embodiment thereof in the accompanying drawings, forming a part of this specification, and in which:—

Figure 1 is a perspective section of a rim, an outer casing, my improved armored inner liner and inner tube.

Fig. 2 is a detail perspective view of one 40 of the armor plates.

Fig. 3 is a detail perspective view of another form of armor plates used in the construction of my improved armored inner liner.

Fig. 4 is a detail perspective view of the 45 third form of armor plates used in the construction of my improved armored inner liner.

Like numerals of reference denote corresponding parts in all the figures of the drawing, referring to which: 1 designates an ordinary rim for holding the casing 2.

Inside this casing 2 is the armored inner liner 3. Within this armored inner liner 3 55 is the inner tube 4.

It will be seen by referring to Fig. 1 that I have left an outer edge 5 of the armored inner liner 3 which may be trimmed off when the armored inner liner 3 is properly installed.

In the construction of the armored inner liner 3, I have used fabric and rubber in constructing the inner liner part. This fabric and rubber part is made thickest at the tread and gradually diminishes in thickness 65 as it reaches the edges 5.

In securing the armor plates to this portion of the armored inner liner 3 a row of plates 6 are first secured along a line marking the lower edge 7 of the armored portion of the device. The clenching members 8 are caused to penetrate the inner liner part and are clenched on the inner side of said inner liner part, the edge 9 extending downwardly. These plates are cut from 70 soft galvanized steel or other suitable material and are rectangular in form and curved to fit a similar arc of the curve on the inner side of the casing 2.

A second row of plates 10 are now secured 80 to the inner liner part 1. These plates 10 are rectangular in form and are formed with clenching members 11, and a centrally located upward and outward bend 12 parallel with the edge 13. By again referring to 85 Fig. 1 it will be seen that the plate 10 overlaps the plate 6 down as far as the bend 12.

The next step is to place a plurality of rows of the plates 10 so that the edge 9 overlaps as far as the bend 12. Finally plates 90 10 meet at the center of the tread at point 14. It will be seen that there is now a portion of only one thickness at the top of the tread. In order to complete the gradual curve and make a double thickness, the 95 plates 15 are now riveted to the plates 10 and the inner liner part of the armored inner liner 3 by means of rivets 16 passing through the holes 17 of the plates 15.

It will be seen by referring to Fig. 1 that 100 all the plates are curved in order to fit snugly along the inner side of the casing 2.

It will also be seen that the plates are laid so that they break joints similar to that of laying shingles. This is done in order to 105 provide a strong resisting surface to penetration.

What I claim is:—

1. In a device of the class described, an inner liner, a row of curved rectangular soft 110

steel plates secured to said inner liner at approximately the centers of the side walls of same, a plurality of rows of rectangular soft steel plates, an upward and outward bend 5 in said plates, secured to said inner liner so as to overlap, a row of rectangular soft steel plates secured by means of rivets to the center of the armor tread, substantially as described for the purpose set forth.

10 2. In a device of the class described, an inner liner, in combination with two lower

rows of rectangular soft steel plates, a plurality of rows of rectangular soft steel plates, an upward and outward bend in said plates, overlapping of said plates, a central row of rectangular plates secured to said inner liner, substantially as described. 15

In testimony whereof I affix my signature.
SAMUEL I. BAER.
